COUNTER RECOIL GOVERNOR FOR A RECOIL TYPE GUN

Irwin R. Barr, Kingsville, and David D. Terwilliger, Baltimore, Md., assignors to Aircraft Armaments, Inc., Baltimore, Md., a corporation of Maryland

Application November 25, 1953, Serial No. 394,320

6 Claims. (Cl. 89—43)

This invention relates to guns and more particularly to a counter recoil governor for recoil type guns employing a fluid cylinder for absorbing the recoil energy and for returning the barrel to the battery position.

Large guns such as those used on warships conventionally employ a fluid cylinder and a piston which move relative to each other in response to barrel movement for absorbing recoil energy. The piston is usually provided with orifices which pass fluid from one side of the piston to the other within the cylinder during the recoil and counter recoil movement. Suitable spring means is also employed to store up part of the recoil energy for effecting the counter recoil movement. Metering pins are carried by the cylinder which cooperate with the piston orifices to decelerate the barrel during the last part of the counter recoil stroke. In operation, when the battery position is reached the barrel should obviously have expended all its energy. If not, the excess energy is absorbed by the barrel support cradle, producing a shock load which sets up vibrations frequently of sufficient magnitude as to damage the gun or associated equipment. If all the energy of the moving barrel is expended before the battery position is reached, the breech mechanism will not have been actuated and the gun will not fire. Since the amount of energy absorbed by the orifice and metering pin system conventionally employed on large guns depends upon the viscosity of the fluid employed in the braking cylinder and since temperature has a definite effect on the viscosity of a fluid, consistent results are not obtained. When the first few rounds of ammunition are fired from the gun, the fluid viscosity is greater than when the gun has been in operation for a longer time. Since the orifices and metering pins used in the present guns do not compensate for changes in fluid viscosity, difficulty is experienced in obtaining proper gun operation. When the fluid is cool, the barrel frequently fails to move into the battery position after firing a round. When the fluid is warm, the barrel slams into the battery position, setting up excessively large vibrations which frequently damage the gun or its associated sighting equipment.

An object of the present invention is to provide a governor for fluid controlled recoil type guns, and the like, which continuously compares the actual barrel velocity with the desired barrel velocity to control the barrel movement and automatically compensate for changes in fluid viscosity whereby the energy in the moving barrel will be properly dissipated.

Another object of this invention is to provide a counter recoil governor which may be used on existing recoil type guns.

Still another object of this invention is to provide a counter recoil governor which is dependable in operation and which may be economically manufactured.

Further and other objects will become apparent to those skilled in the art from a reading of the following description especially when considered in combination

with the accompanying drawing wherein like numerals refer to like parts.

In the drawing:

Figure 1 is a fragmentary perspective view schematically showing the governor of this invention on a fluid controlled recoil type gun.

Figure 2 is a detail sectional side view schematically showing the governor of this invention.

The gun, as schematically shown in Figure 1, includes

10 a barrel 1 carried by a barrel support cradle 2 through collars 3 for limited axial movement relative thereto from a forwardmost battery position as shown in the drawing to a recoil position aft of the battery position. A barrel extension 4 formed rigid with barrel 1 serves 15 as an abutment for engaging cradle 2 and preventing movement of the barrel forwardly of the battery position. Axial movement of barrel 1, produced by forces developed from firing a round of ammunition, is controlled by a fluid-filled cylinder 5 carried by cradle 2. 20 Cylinder 5 is arranged generally parallel with barrel 1 and receives a piston 6 which is rigidly connected with barrel extension 4 through piston rod 7. Piston 6 is provided with a plurality of orifices 8 equipped with check valves (not shown) which regulate the flow of 25 fluid from one side of the piston to the other within the cylinder to control the movement of barrel 1. While the orifice arrangement in piston 6 is generally rather complicated, it is not shown in detail here since any conventional arrangement will be satisfactory for use 30 in conjunction with the counter recoil governor of this invention so long as the rate of energy dissipation during counter recoil is low enough to assure return of the barrel to the battery position under all operating conditions. This requirement may be met in most cases 35 when installing the governor on an existing gun without modifying the orifice arrangement, but by simply removing the metering pins normally employed in the forward end of the fluid cylinder. A counter recoil spring 10 concentrically arranged relative to piston rod 40 7 within cylinder 5 adjacent the aft end 9 thereof absorbs a sufficient quantity of the recoil energy as the barrel moves rearwardly to effect the counter recoil movement back to the battery position.

Counter recoil governor 11 connects with the forward 45 end of cylinder 5 through fluid line 12 and with the aft end of the cylinder through fluid line 13 as shown in Figure 1. A check valve 14 is interposed in line 13 between governor 11 and cylinder 5 to prevent the flow of fluid through the governor during gun recoil movement. Energy dissipation during recoil movement is effected in the normal manner by restricting the flow of fluid through piston orifices 8 and by compressing spring 10.

Barrel position and velocity information for counter 50 recoil governor 11 is obtained by a rack 15 and pinion 16 arrangement wherein rack 15 is suitably carried by barrel extension 4 on the underside thereof and pinion 16 is carried by cradle 2. Pinion 16 connects with a flexible shaft 17 through gear box 18 to rotate the shaft 60 in response to axial movement of barrel 1. The rotational position of the shaft represents the axial position of the barrel relative to the battery position and the rotational velocity of the shaft represents the actual velocity of the barrel. It should be appreciated that any suitable arrangement for rotating shaft 17 may be employed without departing from the teachings of this invention.

The construction of counter recoil governor 11 is 65 shown in Figure 2 wherein the flow of fluid through a master valve 19 regulates the rate of energy dissipation of barrel 1 during counter recoil movement. An inlet

port 20 communicates with fluid line 12 and with a generally cylindrical master valve chamber 21 which slidably receives valve 19 for limited axial movement. An outlet port 22 provides fluid communication between valve chamber 21 and fluid line 13. Master valve 19 comprises a flow control piston 23 and a guide piston 24 connecting with the control piston through a spacer rod 25 so that fluid may flow from inlet port 20 to outlet port 22 through chamber 21 at a rate regulated by the axial position of valve 19.

Valve 19 is positioned within chamber 21 by fluid pressure applied thereto through ports 26 and 27 located at either end of the chamber. Ports 26 and 27 communicate with a pilot valve chamber 28. Fluid from inlet port 20 is fed to pilot chamber 28 through port 29, generally aligned with the inlet port. To assure that fluid will always be applied to the pilot valve chamber 28, even when master valve 19 has completely stopped the flow of fluid to outlet port 22, an annular recess 30 is formed in chamber 21 in alignment with both ports 20 and 29.

The fluid in pilot valve chamber 28 is fed to ports 26 and 27 in accordance with the axial position of a pilot valve 31. Valve 31 comprises a pair of spaced control pistons 32 and 33 which cooperate with an annular recess 34 in communication with port 29 to allow fluid flow into one of the ports 26 or 27 depending upon the axial position of the pilot valve. When valve 31 is centered in chamber 28, ports 26 and 27 are both closed to fluid flow from port 29. When valve 31 is moved to the right of center as viewed in Figure 2, fluid will flow through port 26 and apply pressure to control piston 23 in master chamber 21, causing master valve 19 to move to the right and reduce the fluid flow from the governor into line 13. This increases the back pressure in cylinder 5 to increase the rate of energy dissipation of barrel 1 and hence reduce the barrel velocity. On the other hand, when valve 31 is moved to the left of center, fluid will flow through port 27 and apply pressure to guide piston 24, causing valve 19 to move to the left and increase the fluid flow from the governor to line 13 which reduces the rate of energy dissipation and hence decelerates the barrel less rapidly.

When port 26 is in fluid communication with port 29, port 27 is completely blocked and vice versa. Thus, it is obviously necessary to vent the portion of valve chamber 21 on the one side of valve 19 which is sealed off from port 29 since the fluid contained therein will otherwise prevent the desired movement of the valve. Therefore, vent ports 35 and 36 are employed in pilot valve chamber 28 which feed into outlet port 22 at openings 39 and 40 as shown in Figure 2. Outer pilot valve pistons 37 and 38 are spaced from inner pilot valve pistons 32 and 33 such that only the port 26 or 27 which is sealed off from port 29 is in communication with its associated vent port 35 or 36. Thus as fluid at the inlet pressure is forced against one end of valve 19, the fluid acting against the opposite end thereof is bled off through the associated vent port 35 or 36 against the action of the lower outlet pressure.

From the description set forth hereinabove, it is believed apparent that by simply controlling the movement of pilot valve 31 the fluid back pressure in buffer cylinder 5 will be regulated to control the movement of barrel 1.

Control of pilot valve 31 to assure the proper rate of dissipation of energy of the gun so that barrel 1 will always reach the battery position without an excess of energy is accomplished by generating control forces tending to reduce the difference between the actual barrel velocity and the desired barrel velocity to zero continuously during counter recoil and applying these forces to valve 31.

A pilot valve positioning force proportional to the desired barrel velocity at any barrel position relative to the battery position is produced by a cam and spring arrange-

ment shown in Figure 2. A cam 41, operatively engaging a suitable gear train 42 driven by shaft 43, is shaped to represent the desired velocity curve for the gun barrel during counter recoil. Shaft 43 operatively connects with flexible shaft 17 through a suitable coupling 44 so that rotation of shaft 17 is transmitted to shaft 43. A compression spring 45, acting between pilot valve 31 and cam 41 produces a force representing the desired velocity of the barrel continuously during counter recoil as dictated by the shape of cam 41. Spring 45 is suitably supported by a pair of telescoping members 46 and 47 concentrically arranged relative thereto. Member 46 is slidably carried within pilot valve chamber 28 adjacent one end thereof to butt against pilot valve piston 38. Member 47 is provided with a tongue 48 which is slidably carried in ways 49 to permit only axial movement of the member relative to pilot valve chamber 28. The outer end 50 of member 47 carries a roller 51 through pin 52. Roller 51 is arranged to engage cam 41 so that the axial position of member 47 relative to member 46 is controlled by the rotational position of the cam. In this way, compression spring 45 is caused to produce a positioning force on pilot valve 31 which represents the desired velocity of the gun barrel at all times during counter recoil movement.

The positioning force applied to pilot valve 31 which is proportional to the desired barrel velocity is opposed by a positioning force applied to the pilot valve in the opposite direction which is proportional to the actual barrel velocity. The force representing the actual barrel velocity is produced by a suitable fly-weight type of governor 53 such as is shown in Figure 2. A transverse bracket 54 is rigidly attached to a shaft 55 rotatably carried by support 56. Bracket 54 swingably carries a pair of weights 57 and 58 so that as shaft 55 is rotated, centrifugal force causes the weights to swing outwardly from the shaft. Projections 59 and 60 on weights 57 and 58 engage a collar 61 slidably carried by shaft 55 and cause it to move along the shaft as the rotational velocity increases. A compression spring 62 acts between collar 61 and axially movable flange member 63 to produce a positioning force representing the rotational velocity of shaft 55 due to the action of weights 57 and 58 when rotated. Flange member 63 is supported by a shaft 64 which is slidably received within an aperture 65 formed in shaft 55 and by a second shaft 66 supported from within pilot valve chamber 31 through idler pistons 67 and 68. The force produced by compression spring 62 is transmitted to pilot valve piston 37 through flange member 63 and shaft 66. To prevent shaft 66 and its associated idler pistons 67 and 68 from rotating when shaft 55 is rotated, flange member 63 is rotatably connected to shaft 66 through suitable bearing means 69, and idler piston 68 is provided with a key 70 adapted to slide in keyway 71 formed in valve chamber 28.

Rotation of the fly-weight type of governor 53 to produce a pilot valve positioning force representing the actual barrel velocity is accomplished by operatively connecting shaft 55 to shaft 43 through a suitable gear train 72.

An overrunning clutch 73 associated with shaft 43 provides a positive drive for governor 53 during counter recoil of barrel 1 and allows shaft 55 to slow down gradually from friction forces even though shaft 43 is stopped abruptly.

The operation of the device is believed obvious from a reading of the foregoing description. When the gun is fired, the recoil forces are absorbed in the conventional manner as the barrel moves aft by the regulated fluid flow through orifices 8 in piston 6 and by the compressing of the counter recoil spring 10. Check valve 14 in fluid line 13 prevents fluid flow through counter recoil governor 11 during the recoil movement. When all the recoil energy is dissipated, counter recoil spring 10 urges barrel 1 forwardly towards the battery position. During this return or counter recoil movement, all or a controlling

portion of the fluid in cylinder 5 is forced through counter recoil governor 11. The rate at which the fluid is allowed to flow through the counter recoil governor is regulated by continuously comparing the actual and the desired barrel velocities.

Counter recoil movement of barrel 1 causes rotation of flexible shaft 17 and shaft 43 through the rack 15 and pinion 16 arrangement shown in Figure 1. Cam 41, driven from shaft 43, as shown in Figure 2, is shaped to compress spring 45 a varying amount depending upon the axial position of barrel 1 to produce a force representing the desired barrel velocity. At the same time cam 41 is operating to provide a force representing the desired barrel velocity, fly-weight governor 53 compresses a spring 62 to produce a force representing the actual barrel velocity. These two forces are applied to pilot valve 31 to control the operation of counter recoil governor 11. If the barrel is moving at a velocity different from the desired velocity, the velocity error is detected by springs 45 and 62, causing valve 31 to move so as to modify the rate of fluid flow from the forward end of cylinder 5 and thereby cause the barrel to again travel at the desired velocity. This velocity control inherently causes the proper dissipation of energy. The corrective action of the counter recoil governor is applied to the system continuously to always maintain the actual barrel velocity substantially equal to the desired barrel velocity during the return stroke irrespective of changes in the fluid viscosity. When the barrel reaches the battery position, its kinetic energy will have been completely expended so that the vibrations normally experienced with conventional buffer arrangements is eliminated.

The counter recoil governor described hereinabove may be used with equal facility for controlling recoil movement of the gun barrel in the same manner as the counter recoil movement is controlled. Obtaining control by comparing the actual barrel velocity with the desired barrel velocity simplifies the gun design and assures uniform gun operation even though the viscosity of the fluid in the buffer cylinder changes and even though different sized rounds of ammunition are fired.

The speed control arrangement wherein the actual and desired velocities of the barrel are compared may obviously be used with equal facility to control the motion of a moving member of any kind and is not necessarily limited to use in connection with a gun.

It is to be understood that certain alterations, modifications and substitutions may be made to the instant disclosure without departing from the spirit and scope of the invention as defined by the appended claims.

We claim:

1. Counter recoil regulating means for recoil type guns having a barrel support and a barrel reciprocable with respect thereto, a fluid cylinder carried by said barrel support, a piston carried within said cylinder and fixed to said barrel for reciprocating motion therewith, regulator means connecting with said cylinder at either end thereof and providing fluid communication to both sides of said piston whereby barrel movement may be regulated by controlling the flow of fluid from said cylinder, said regulator means including a master valve controlling the flow of fluid from said cylinder, a pilot valve controlling the master valve, means sensing the actual speed of barrel movement for producing a pilot valve positioning force proportional thereto, means sensing barrel movement for producing a pilot valve positioning force proportional to the desired velocity of the barrel, means for applying the difference between the forces produced by the last two mentioned means to said pilot valve for controlling said master valve and regulating the flow of fluid from said cylinder to obtain the desired barrel counter recoil movement.

2. Counter recoil regulating means for recoil type guns having a barrel and a barrel support comprising, a fluid cylinder carried by said gun, a piston carried within said

cylinder and fixed to said barrel for axial movement therewith relative to said barrel support, governor means carried by said gun for producing a force representing the actual velocity of said barrel relative to said barrel support, a cam carried by said gun, said cam being operatively connected to said barrel and shaped to represent the desired velocity of said barrel, spring means compressible by said cam to produce a force representing the desired velocity of said barrel, valve means regulating the flow of fluid within said cylinder from one side of said piston to the other, and valve control means operable by the forces produced by said governor means and said spring means for actuating said valve means to effect the desired barrel movement.

3. Counter recoil regulating means for recoil type guns having a barrel and a barrel support comprising, a fluid cylinder carried by said gun, a piston carried within said cylinder for axial movement relative thereto, said piston being fixed to said barrel for movement therewith relative to said barrel support, means for sensing barrel movement relative to said barrel support for producing a force proportional to the actual velocity of said barrel, means for sensing barrel movement relative to said barrel support for producing a force proportional to the desired velocity of said barrel,

20 25 30 35 40 means connecting with said energy damping means for generating a force representing the desired barrel velocity, means connecting with said energy damping means for generating a force representing the actual barrel velocity, and means comparing the forces generated by the last two mentioned means and operatively connecting with said energy damping means for varying the damping action thereof to maintain the actual barrel velocity substantially equal to the desired barrel velocity.

4. In a recoil type gun having a barrel support, and a barrel movable relative to the support for absorbing recoil loads, energy damping means carried by the barrel support for regulating the movement of the barrel, means connecting with said energy damping means for generating a force representing the desired barrel velocity, means connecting with said energy damping means for generating a force representing the actual barrel velocity, and means comparing the forces generated by the last two mentioned means and operatively connecting with said energy damping means for varying the damping action thereof to maintain the actual barrel velocity substantially equal to the desired barrel velocity.

5. A gun comprising a barrel support, a gun barrel carried by said support for limited recoil movement relative thereto, a piston carried by said barrel for movement therewith relative to said barrel support, a fluid cylinder carried by said barrel support and containing said piston for sliding movement therein, fluid flow control means providing fluid communication from one side

45 50 55 60 65 of said piston to the other within said cylinder, a rack and pinion carried by said gun, by said rack being fixed to said barrel and movable therewith relative to said support to drive said pinion, a shaft operatively connecting with said pinion for rotational movement therewith, a pair of spring means carried by said fluid flow control means, cam means driven by said shaft and engaging one of said pair of spring means for deflecting the latter and producing a force representing the desired velocity of said barrel, governor means connected to said shaft and engaging the other of said pair of spring means to deflect said other spring means for producing a force representing the actual velocity of said barrel, and means actuatable by both said spring means for regulating said fluid flow control means and maintaining the actual barrel velocity nearly equal to the desired barrel velocity.

6. A governor for controlling the velocity of a movable member comprising, a shaft, means carried by said movable member and connecting with said shaft to produce rotation thereof at a rate proportional to the actual velocity of said movable member, a pair of opposed spring means, variable control means connecting with said movable member for regulating the movement thereof in accordance with the combined force exerted by said spring means, cam means driven by said shaft at a rate proportional to the actual velocity of said movable

member and engaging one of said pair of spring means for deflecting the latter and producing a force representing the desired velocity of said movable member, a second shaft operatively connecting with the first-mentioned shaft, and a weight carried by said second shaft for radial movement proportional to the rotational velocity thereof, the other of said pair of spring means being deflected by the movement of said weight to produce a force representing the actual velocity of said movable member whereby to vary said control means in cooperation with the other of said pair of spring means to maintain the actual velocity of said movable member nearly equal to the desired velocity.
